CLAIM

The ornamental design for a hospital gas delivery system, as shown and described.

DESCRIPTION

FIG. 1 is a front elevational view of a hospital gas delivery system, showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view of a second embodiment of the hospital gas delivery system showing my new design;

FIG. 8 is a right side elevational view thereof;

FIG. 9 is a rear elevational view thereof;

FIG. 10 is a left side elevational view thereof;

FIG. 11 is a top plan view thereof; and,

FIG. 12 is a bottom plan view thereof.
